(57) **CLAIM**

The ornamental design for a food bar, as shown and described.

DESCRIPTION

The patent or application file contains at least one drawing executed in color. Copies of this patent or patent application publication with color drawing(s) will be provided by the Office upon request and payment of the necessary fee.

FIG. 1 is a top plan view of a first embodiment of a food bar; FIG. 2 is a bottom plan view of the food bar of FIG. 1; FIG. 3 is a left side elevation view of the food bar of FIG. 1;

FIG. 4 is a right side elevation view of the food bar of FIG. 1;

FIG. 5 is a front elevation view of the food bar of FIG. 1; FIG. 6 is a rear elevation view of the food bar of FIG. 1; FIG. 7 is a top plan view of a second embodiment of a food bar;

FIG. 8 is a bottom plan view of the food bar of FIG. 7; FIG. 9 is a left side elevation view of the food bar of FIG. 7;

FIG. 10 is a right side elevation view of the food bar of FIG. 7;

FIG. 11 is a front elevation view of the food bar of FIG. 7; FIG. 12 is a rear elevation view of the food bar of FIG. 7; FIG. 13 is a top plan view of a third embodiment of a food bar;

FIG. 14 is a bottom plan view of the food bar of FIG. 13; FIG. 15 is a left side elevation view of the food bar of FIG. 13;

(Continued)

FIG. 16 is a right side elevation view of the food bar of FIG. 13;
 FIG. 17 is a front elevation view of the food bar of FIG. 13;
 and,
 FIG. 18 is a rear elevation view of the food bar of FIG. 13.
